CLAIM

The ornamental design of a container with cover, as shown and described.

DESCRIPTION

FIG. 1 is a perspective view of the container with cover showing my new design;

FIG. 2 is a front view of the container with cover;

FIG. 3 is a side view of the container with cover;

FIG. 4 is a back view of the container with cover;

FIG. 5 is a top view of the container with cover; and,

FIG. 6 is a bottom view of the container with cover.

The broken lines in the drawing are included for the purpose of illustrating and form no part of the claimed design.
